RADIUS WHEEL DRESSER

Arthur Greig, River Rouge, Mich., assignor to
U. S. Tool and Mfg. Co., a corporation of Michigan

Application July 29, 1944, Serial No. 547,195

5 Claims. (Cl. 125—11)

My invention pertains to dressers for dressing abrasive wheels for precision grinding and more particularly to radius and angle dressers.

It is an object of my invention to provide an improved wheel dresser which is more convenient, accurate and reliable for dressing abrasive wheels for precision grinding.

It is also an object of my invention to provide an improved angle correcting radius wheel dresser, and method of operation.

It is a further object of my invention to provide an abrasive wheel dresser which not only does the work of an ordinary radius dresser but which may also be utilized for grinding compound and compound complex forms on flat form tools and the like.

Further objects and advantages are within the scope of the invention, such as relate to the arrangement, operation and function of the related elements of the structure, to various details of construction and to combinations of parts, elements per se, and to economies of manufacture and numerous other features as will be apparent from a consideration of the specification in conjunction with the drawings disclosing specific embodiments of the invention, in which:

Fig. 1 is a side elevational view showing my improved angle correcting radius wheel dresser;

Fig. 2 is an end elevational view thereof;

Fig. 3 is a longitudinal or axial sectional view taken along line 3—3 in Fig. 2;

Fig. 4 is a cross sectional view taken along line 4—4 as shown in Fig. 1.

Fig. 5 is an enlarged fragmentary plan view of the end of the crank with the diamond dresser element therein;

Fig. 6 is an end elevational view, partially diagrammatic and broken away, illustrating the use of the dresser;

Figs. 7 and 8 are diagrammatic views illustrating positions in which the dresser may engage a wheel to be dressed;

Fig. 9 is a plan view showing a position in which the dresser may be used for dressing for compound-complex angle dressing;

Fig. 10 is a fragmentary side elevational view of a flat form tool, and

Fig. 11 is a fragmentary detail view.

Referring more particularly to Figs. 1, 2 and 3, of the drawings, my wheel dresser comprises a substantially cylindrical body 11 having a bearing aperture 13 extending axially therethrough. A main shaft 15, having a curved radius crank 17 extending rigidly from one end, passes through the axial aperture through the body and has a convenient adjusting handle 19 and hub 21 se-

cured rigidly on the other end, as by means of a screw 22 and a key 23. The aperture in the body is provided with enlarged counter-bores 25 and 27 in the opposite ends for snugly receiving the outer rings of two tapered roller bearings 31 disposed in opposing relation for rotatively supporting the main shaft whereupon the inner bearing rings are snugly disposed. The intermediate portion of the shaft which receives the inner race rings of the roller bearings is of reduced diameter providing a shoulder near the crank end which firmly abuts the outer end of the inner ring of the adjacent tapered roller bearing. The other end of the reduced portion of the main shaft is threaded for receiving a nut 33 thereon firmly abutting the outer end of the inner ring of the other roller bearing which is disposed in an opposing relation to the bearing adjacent the crank. The nut 33 may be secured in any well known manner, as by a lock washer for example.

The end of the body 11 adjacent the crank end of the shaft is closed and sealed around the shaft by means of a closure ring 35 secured to the body, as by screws 37, and having a sealing gland sealed by any suitable shaft sealing ring 39, of which a suitable well known type is represented, comprising a leather collar 38 clamped around on the shaft 15 by a spring 40 and enclosed in an annular sheet metal ring 42 as shown in detail Fig. 11. The counter-bore in the other end of the body is longer in order to provide ample space for the bearing securing nut 33 and a second closure ring 41 is secured on that end of the body by means of screws 37, the second closure ring also being similarly provided with a gland receiving any suitable seal 39 for sealing around the shaft to retain lubricant and exclude grit. An indicator ring 43 is disposed upon the shaft 15 between the second closure ring 41 and the hub 21 and this ring is rigidly secured to rotate with the shaft, as by means of the same key 23 which also secured the hub to the shaft. The ring 43 is provided with an indicator finger 44 which projects adjacent the second closure ring which is provided with a suitable scale 45 for showing the various angular positions to which the main shaft 15 is adjusted in the body. The main shaft 15 may be adjusted through any desired angle up to a substantial angle of about 40° and it is limited to any desired angular swing by means of a pair of stop screws 47 which may be moved, to various positions as represented dotted in Fig. 2, and clamped in a T-slot 49 in the closure ring 41 so as to engage opposite sides of the indicator

finger 44, as the handle 19 is oscillated from side-to-side.

The end of the curved radius crank 17 is provided with a radially directed aperture 51 wherein in a wheel dresser member 53 is slidably disposed. In the end of the crank 17 is a screw 55 having a knurled knob 57 for conveniently securing the dresser element 53 in any position according to the radius desired. To facilitate this adjustment, a radius determining measuring arm 59, having an L shaped head 61, is provided. This may be inserted into a bushing 60 disposed in a radial aperture in the end of the crank to insure that the wheel dresser member 53 may be quickly and accurately positioned when moved radially, as indicated in dotted lines in Fig. 1. A suitable thickness gauge 62 may be inserted between the point of the wheel dresser 53 and the head 61. Also the member 61 may be moved radially and secured in various positions, as represented dotted, by means of a knurled screw 63.

The body 11 in which the main shaft is supported, and wherein it may be adjusted on an axis designated as the main axis, is in turn adjustably supported for adjustable angular rotation on an auxiliary axis which is at right angles to said main axis. As shown in Fig. 2, and more specifically in Fig. 4, this is accomplished by mounting the body 11 upon the inner end of an auxiliary shaft 65 which passes through an upstanding wall 67 rising from one edge of a pedestal flange 69. Opening through the side wall of the body at right angles to the axis of the main shaft 15 is an aperture wherein one end of the auxiliary shaft 65 is inserted and secured, as by keys 71. The other end of the auxiliary shaft 65 projects through to the other or outer side of the wall 67 and it is threaded for receiving a hub 73 and a handle 75 whereby to conveniently control the adjustment of the body angularly on the auxiliary axis. The outer side of the wall is provided with an annular socket 77 concentric with the shaft 65 for receiving the adjacent end of the hub 73 when it is screwed upon the end of the auxiliary shaft. A washer 79 is provided on the shaft between the hub and the bottom of the socket. The hub 73 is provided with an aperture 81 which opens from the inner end of the hub and which is of a suitable diameter for receiving a compressed spring 83.

The inner side of the wall 67 engaging the body 11 thereon, and the adjacent portion of the body, are provided with interfitting engageable surfaces. For this purpose the inner side of the wall 67 is provided with a baring projection 85 concentric with the auxiliary shaft 65 and extending inwardly over the pedestal flange 69 and entering a suitable socket 87 in the adjacent side of the pivoted body. The bearing projection 85 is tapered, presenting a frusto-conical surface, and its socket in the adjacent body is correspondingly shaped to cooperate therewith so that by drawing the auxiliary shaft 65 firmly in the wall by means of the hub 73 screwed thereon, the body is rigidly supported from the wall for very accurate angular rotation or adjustment on the auxiliary axis. Also, for this purpose, the base of the bearing projection 85 is preferably provided with an annular groove for receiving an interfitting annular flange 89 projecting therein from the outer edge of the tapered socket in the body. As Fig. 2 shows, a calibrated scale 91 is provided on the portion of the body which engages the bearing projection for cooperation with an index mark 93 on

the latter, or the relation of these may be reversed as by placing the scale on the stationary part and the index mark on the adjustable body, as will be understood. In this manner accurate positioning and movement of the body 11 are assured and the adjusted angular position of the body on the auxiliary axis is readily determined.

In operation, if it is desired to make a convex cutting face on the abrasive wheel 95, represented in Fig. 7, the diamond point of the dresser element 53 is positioned under the center of the wheel. Initially the radial position of the dresser element in the crank 17 is set below the axis of the shaft 15 by a distance equal to the radius to be dressed on the wheel. As shown in Fig. 6, the pedestal of the dresser usually sets upon the chuck 97 of the grinder machine, against the parallel bar 99. For a convex surface on the wheel, which is a circular arc in cross-section, the axis of the shaft 15 is set at zero angle, or parallel, to the horizontal or chuck 95, as represented in Fig. 7, and with the point of the diamond engaging the wheel below its center, the handle 19 is oscillated to move the point across the face of the rotating wheel.

But when dressing a wheel for forming a groove 101 in a flat form tool 103, shown in Fig. 10, having an angle B, it is necessary to consider that the cross-section of the groove where it intersects the angular surface will be substantially different. If it is desired, for example, to have a circular cross-section where the groove 101 intersects the angular surface, the axis of the shaft 15 must be inclined at a similar angle B to the chuck to make a modified convex surface on the face of the wheel. The wheel will then form a groove 101 of a properly conformed cross-section so that it will have the desired, circular, or other desired shape where it intersects on the angular surface. For a compound-complex angle, as where there is also another face intersecting, the angle of the pedestal of the dresser is then inclined away from the parallel bar 99 using the front right corner as the pivot point, to the directly read angle that is called for (as this information may be provided on the blue-print), as represented in Fig. 9. In this manner the requirements for various compound-complex angles can be conveniently met. For dressing a concave surface in the face of a wheel, the diamond point 53 is set above the axis of rotation of shaft 15 by an amount equal to the radius of curvature desired, and the dresser is utilized in the manner previously described.

This accurate, direct reading dresser obviates the costly labor wasting practice used in the old style hit-and-miss method of dressing radii by guessing where and how much back of center of the wheel the common dresser should be placed in order to produce the right radius.

It is apparent that within the scope of my invention modifications and different arrangements may be made other than herein disclosed, and the present disclosure is illustrative merely, the invention comprehending variations thereof.

I claim:

1. A radius and angle wheel dresser comprising, a base having a pedestal flange with an upstanding wall rising from along one edge thereof, a bearing projection projecting from the inner side of said wall and extending over the pedestal flange, said bearing projection having a circular cross-section, a bearing aperture passing through said wall and concentrically through said bearing projection, a body having a bearing aperture

extending therethrough and an auxiliary aperture opening through the side wall of said body perpendicularly to the axis of said bearing aperture, the outer portion of said body around the outer end of said auxiliary aperture being suitably conformed for cooperative interfitting engagement with said bearing projection, an auxiliary shaft having one end secured into said auxiliary aperture in said body and passing rotatively through the bearing aperture in said bearing projection of said wall, the end of said shaft projected through to the outer side of said wall being threaded, adjusting means secured upon the outer end of said auxiliary shaft, a main shaft passing rotatively through the bearing aperture in said body, a radius crank extending rigidly from one end of said main shaft, a wheel dresser member extending movable radially through the crank for convenient adjustment toward or away from the axis of said main shaft, means for securing said wheel dresser element in any adjusted radial position in said crank, manual means secured upon the other end of said main shaft for rotating the main shaft and wheel dresser to various desired positions, cooperative calibrated scale and index means for showing the angular position of the main shaft relative to the body, and calibrated scale and index means cooperatively on said wall bearing projection and body for showing the angular position of the body relative to said wall as adjusted upon the auxiliary axis.

2. In combination in a radius and angle wheel dresser, a base having a pedestal flange with an upstanding wall rising along one edge thereof, a bearing projection extending from the inner side of said wall over said pedestal flange, said bearing projection being circular in cross-section, a bearing aperture passing through said wall and concentrically through said bearing projection, a substantially cylindrical body having a bearing aperture extending axially therethrough and an auxiliary aperture opening through the side wall of said body perpendicularly to the main axis of the body, the outer portion of said body around the outer end of said auxiliary aperture and adjacent the end of said bearing projection being suitably conformed for cooperative interfitting engagement therewith, an auxiliary shaft having one end secured into said auxiliary aperture in said body and passing rotatively through the bearing aperture in said bearing projection of said wall, the end of said shaft projected through to the outer side of said wall being threaded, manual adjusting means threadably secured upon the threaded end of said auxiliary shaft, a main shaft passing rotatively through the axial aperture in said body, a pair of taper roller bearings disposed spaced apart in opposing relations for rotatively supporting said main shaft in said body, a curved radius crank extending rigidly from one end of said main shaft, a wheel dresser member extending radially through the crank for convenient adjustment toward or away from the axis of said main shaft, means firmly securing said wheel dresser element in any adjusted position in said crank, manual means secured upon the other end of said main shaft for rotating the main shaft and wheel dresser to various desired positions, cooperative calibrated scale and index means for showing the angular position of the main shaft relative to the body, and calibrated scale and index means cooperatively on said wall bearing projection and body for showing the angular position of the body relative to

said wall as adjusted upon the auxiliary axis, and closure means for closing and sealing around the end of said main shaft and body.

3. In a radius and angle wheel dresser the combination in accordance with claim 1 and further characterized by having a pair of tapered roller bearings spaced apart in opposing relations in said body for rotatively supporting said main shaft, and stop means for stopping said main shaft in any adjusted angular position.

4. A radius and angle wheel dresser in accordance with claim 2 and further characterized by having a T-slot opening from said second closure ring and extending curved around the axis of said main shaft, and a pair of stop screws adjustable in said T-slot to stop said main shaft in any adjusted position, and said index means being secured to and projecting from said main shaft over said T-slot.

5. In a radius and angle wheel dresser the combination of, a base having a pedestal flange with an upstanding wall rising from along one edge thereof, a bearing projection projecting from the inner side of said wall and extending over the pedestal flange, said bearing projection having a circular cross-section, a bearing aperture passing through said wall and concentrically through said bearing projection, a substantially cylindrical body having a bearing aperture extending axially therethrough, and an auxiliary aperture opening through the side wall of said body perpendicularly to the main axis of the body, the outer portion of said body around the outer end of said auxiliary aperture and the end of said

35 bearing projection being suitably conformed for cooperative interfitting engagement, an auxiliary shaft having one end secured into said auxiliary aperture in said body and passing rotatively through the bearing aperture in said bearing

40 projection of said wall, the end of said shaft projected through to the outer side of said wall being threaded, rotative means threadably secured upon the threaded end of said shaft, a main shaft passing rotatively through the axial aperture in said body, a pair of taper roller bearings disposed spaced apart in opposing relations for rotatively supporting said main shaft in said body, a radius crank extending rigidly from one end of said main shaft, said crank being adapted

50 for radially supporting a dresser element for convenient adjustment toward or away from the axis of said main shaft, means for firmly securing a wheel dresser element in any adjusted position in said crank, manual means secured upon the

55 other end of said main shaft for rotating the main shaft and wheel dresser to various desired positions, calibrated scale and index means cooperatively on said wall bearing projection and body for showing the angular position of the body relative to said wall as adjusted upon the auxiliary axis, a closure ring, a shaft seal in said ring for closing and sealing around the end of said

60 main shaft adjacent the crank, a second closure ring, a shaft seal in said ring for closing and sealing around the end of the main shaft adjacent the manual adjusting end of the main shaft, a T-slot curved concentrically of said shaft in said second closure ring, locking screws in said T-slot, and an indicating pointer on said main

65 shaft and extending radially adjacent said second closure ring for showing the angular position of said shaft in said body and for engagement between said locking screws for securing the main shaft.
